UNITED STATES PATENT OFFICE.

ADDISON A. CARDWELL, OF RYE, NEW YORK.

HUMIDIFYING MEANS FOR USE IN CONJUNCTION WITH HEATING APPARATUS.

1,117,784.

Specification of Letters Patent.

Patented Nov. 17, 1914.

Application filed March 16, 1914. Serial No. 825,036.

To all whom it may concern:

Be it known that I, ADDISON A. CARDWELL, a citizen of the United States, and a resident of Rye, county of Westchester, and 5 State of New York, have invented certain new and useful Improvements in Humidifying Means for Use in Conjunction with Heating Apparatus, of which the following is a specification.

10 The object of my present invention is to afford simple but effective automatic means whereby the heat of an ordinary steam, hot water, or hot air furnace may be utilized in furnishing humidifying vapor to the air in 15 one or more apartments or inclosures, to counteract the deleterious effects of an abnormally dry atmosphere, substantially as set forth in my concurrent application, Serial No. 820,404, filed Feb. 24th, 1914, so 20 that lack of desirable atmospheric moisture caused by artificial heating may be compensated for, in whole and in part, and so that the humidifying vapor may be impregnated if desired with a volatile perfume, deodorizer, disinfectant or medicament, before introduction into the air to be humidified.

25 In the accompanying drawings, Figure 1, is a diagrammatic view representing symbolically the practical application of my invention; Fig. 2 is a front view of the feed trap, partly broken away; Fig. 3, is a top view of the trap; Fig. 4, a vertical sectional elevation taken upon plane of line 4—4 Fig. 3; Fig. 5, a sectional detail of the impregnator.

30 A, represents symbolically a furnace of any character such as used for heating dwellings, &c., and it may be of steam, hot air, or hot water, or any other type, according to circumstances,—my vaporizing chamber *v*, being positioned in the combustion chamber *a*, as a convenient situation for the acquisition of the heat essential to the operation of my system of humidification; or 35 the necessary heat to effect evaporation may be imparted to the vaporizing chamber *v*, by any other means, as may be found most expedient in practice.

40 The vapor generated in the chamber *v*, is conducted by one or more pipes *a'*, to the apartment or apartments, the air in which is to be humidified; or in the case of a hot air furnace the vapor may be conducted from the vaporizing chamber *v*, directly 45 into the hot air chamber of the heater, to mingle and flow with the hot air supply.

Where a stand pipe *a²*, is used as a means of distribution it may be inclosed in the wall structure and provided with a discharge hood *a³*, opening into the apartment. 60

When it is desired to impregnate the moist vapor with a volatile perfume, deodorant, disinfectant or medicament, I provide the stand pipe *a²*, with a receptacle *a⁴*, for such volatile material, preferably in the 65 form of a cup connected to the stand pipe by means of a short duct *d⁵*, through which the volatile emanations escape from the cup *a⁴*, into the stand pipe, to be absorbed by the vapor passing therethrough. 70

Water is supplied to the evaporating chamber *v*, through the medium of my feed trap *B*, interposed between a branch *C*, of the water service pipe and said evaporator *v*, as indicated in Fig. 1,—*c*, being a valve 75 in the service pipe *C*, by means of which the water may be shut off from said feed trap when desired, as at night when the fire in the furnace is banked, when the heater is 80 out of service, or when the atmosphere is surcharged with moisture; or when it is desired to discontinue the supply of humidifying vapor for any reason.

The feed water trap *B*, is formed with four compartments, a receiving and settling 85 compartment *b¹*, into which the water enters from the supply pipe *C*, the filter compartment *b²*, the drip compartment *b³*, and the discharge compartment *b⁴*, from which the water escapes through the discharge pipe *d*, 90 the vaporizing chamber *v*, which latter is on a lower level than the feed water trap *B*, as represented in Fig. 1.

The supply pipe *C*, enters the receiving compartment *b¹*, some distance above the 95 bottom thereof, so that the lower portion of the compartment *b¹*, constitutes a settling pocket *b¹¹*, for the reception of the coarser sediment, which may be blown or washed out from time to time through the hole *b¹²*, 100 closed normally by the screw plug *b¹³*. As the passage of water through the feed trap *B*, is comparatively slow, escaping therefrom as it does drop by drop as hereinafter set forth, there is ample time for the gravitation of the coarser particles of foreign matter in the feed water into the pocket *b¹¹*, before said feed water enters the filtering chamber *b²*, through the duct *b⁵*, in the partition wall *b⁶*, of the trap *B*, as will be 110 understood by reference particularly to Fig. 2, of the drawings.

The filtering compartment b^2 , and the drip chamber b^3 , are in vertical alinement, or substantially so, and are separated by a transverse partition b^{23} , of ample thickness, 5 formed with a valve seat e , interposed in the drip duct b^x , which extends through the partition b^{23} , from the bottom of the filtering chamber b^2 , to the top of the drip chamber b^3 —the available area of said valve seat 10 and duct for the passage of water being controlled by the needle valve E , screwed into the said partition b^{23} , the outer end of said screw valve E , projecting through the front of the casing and being provided with 15 means whereby the screw valve may be readily manipulated to regulate the escape of water from the filtering chamber b^2 .

A dial e' , may be arranged on the face of the casing concentric to the needle valve E , 20 and the latter may be provided with an index e^2 , to facilitate the setting of the valve. An arch or dome f , of wire gauze or similar foraminous material may be placed in the bottom of the filter compartment b^2 , 25 to space the filtering material F , away from the drip duct b^x , as shown in Fig. 2.

In order to centralize the drip from the duct f^x , and insure its descent visibly when observed through a sight glass s , mounted 30 for the purpose in the front of the trap B , I provide a funnel g , mounted on a bracket g' , the funnel being positioned in alinement with the lower end of said duct b^x , as shown in Fig. 2.

35 The lower portion of the drip chamber b^3 , merges into the lower portion of the discharge chamber b^4 , as shown in section in Fig. 3, and the discharge conduit d , connected with the latter prescribes the water 40 level therein, and in the drip chamber b^3 , also,—said water level being discernible through the sight glasses s , s' , provided for purposes of observation. Thus the drip from the filter chamber b^2 , may not only be 45 observed, or the absence thereof noted, but it is also possible to ascertain by a comparative glance whether the trap is properly sealed and operative.

The U-shaped connection between the 50 drip chamber b^3 , and the discharge chamber b^4 , affords an additional trap or well for the elimination from the actual feed escaping through the exit pipe d , of any matter other than liquid that might by any possibility 55 escape the settling pocket b'' , and filtering material F . By this means the evaporating chamber v , is effectually protected against all danger of incrustation by sedimentary deposits that might otherwise result therein 60 during the evaporation of the feed water.

A blow off or wash out aperture is provided at the bottom of the U-shaped connection between the drip chamber b^3 , and the discharge chamber b^4 , said aperture being 65 closed normally by a screw plug b^7 . Like-

wise the upper ends of the receiving chamber b' , of the filter chamber b^2 , and of the discharge chamber b^4 , are closed respectively and normally by screw caps or plugs b^8 , b^9 , b^{10} , which affords means of access to 70 the said compartments when necessary.

A water seal h , is provided at the junction of the stand pipe a' , with the vapor discharge pipe a'' , from the evaporating chamber v . This trap which is simply a 75 U-shaped pipe connection open to the atmosphere at its outer end, prevents the escape of vapor at that point while affording an escape for an overflow of water should the heat in the evaporating chamber v , be 80 insufficient to vaporize the feed from the trap B . Presumably the valve c , in the supply pipe C , is closed when the fire in the heater A , is banked for the night, or the heater is not in use, and the provision of the 85 overflow trap h , is simply a matter of precaution to prevent a head of water in the distribution or stand pipe a' .

The needle valve E , admits of the regulation of the feed drip with accuracy, according to requirements. The elimination of all foreign matter from the water feed prevents clogging and incrustation, and insures a supply of humidifying vapor uncontaminated with objectionable odor of any kind. 95

What I claim as my invention and desire to secure by Letters Patent is,

1. In humidifying apparatus of the character designated, a feed water trap comprising a receiving and settling compartment, a filter compartment, a drip compartment and a discharge compartment, means for supplying a liquid to said first-named compartment above the bottom thereof, the vertical partition wall of the trap having a duct 100 near its upper end, a transverse partition extending from the vertical partition and having a valve-controlled passage, and a U-shaped connection between the lower end of the drip compartment and the discharge 105 compartment.

2. In humidifying apparatus of the character designated, a feed water trap comprising a receiving and settling compartment, a filter compartment, a drip compartment and a discharge compartment, means for supplying a liquid to said first-named compartment above the bottom thereof, the vertical partition wall of the trap having a duct 115 near its upper end, a transverse partition extending from the vertical partition and having a valve-controlled passage, a U-shaped connection between the lower end of the drip compartment and the discharge compartment, and a filter in said filtering compartment supported on said transverse partition. 120

3. In humidifying apparatus of the character designated, a feed water trap comprising a receiving and settling compartment, a 130

filter compartment, a drip compartment and a discharge compartment, means for supplying a liquid to said first-named compartment above the bottom thereof, the vertical 5 partition wall of the trap having a duct near its upper end, a transverse partition extending from the vertical partition and having a valve-controlled passage, a U-

shaped connection between the lower end of the drip compartment and the discharge 10 compartment, and a vertical diaphragm extending into said U-shaped connection.

ADDISON A. CARDWELL.
